UNITED STATES PATENT OFFICE

LAWRENCE FRITZ, OF PORTLAND, OREGON

SPEED CHANGE DEVICE FOR SOUND REPRODUCERS

Application filed May 10, 1930. Serial No. 451,473.

My invention relates to the reproduction of sound by use of a rotatable record and relates particularly to the reproduction of sound in connection with a motion picture film. At the present time that type of sound reproduction in connection with motion pictures which utilizes a record synchronously operated in connection with the motion picture machine, uses a record of relatively large diameter adapted to rotate at approximately 33½ R. P. M. The ordinary phonograph record operates at approximately 78 R. P. M. and thus when special features, music, and the like are run using the latter type of record, it is necessary to provide two separate reproducing mechanisms, one synchronized with the motion picture projection machine and operated at 33½ R. P. M., and the other independent thereof and operating at 78 R. P. M. This requires duplication of mechanism in the projection room in which space can not easily be spared, or which causes the mechanism to be spread over too large an area to be carefully checked by the operator. It is impractical to provide a speed change device in connection with the turn table synchronized with the motion picture projecting machine, and in this manner to eliminate the higher speed apparatus, for the reason that absolute synchronization of such sound reproduction must be maintained with respect to the film.

The object of my invention is to provide a speed change device in the form of an attachment adapted to be arranged on top of the ordinary turn table of a sound reproducing device and to be anchored relatively thereto without affecting the driving connections for the latter and to operate an auxiliary turn table at a different speed. Such attachment is relatively thin so that said attachment with the record in place thereon may be arranged under the ordinary tone arm and so that the entire assembly will be centered by the upstanding central pin on such turn table.

This object is attained by providing two stacked discs, one mounted upon the other and operatively connected by a train of gears or similar mechanism, in part carried by a

member adapted to be fixed relatively. Such apparatus is adapted to produce a difference in speed of rotation of the lower disc, which is in engagement with the turn table.

Details of construction and mode of operation are hereinafter described with reference to the accompanying drawings, in which:

Fig. 1 is a fragmentary view of sound reproducing apparatus in connection with which my invention is adapted for use;

Fig. 2 is a side elevation of one embodiment of my invention; and

Fig. 3 is a view taken on the line 3—3 in Fig. 2.

My invention is adapted to be used with the turn table *a* of sound reproducing apparatus to produce differential speed with relation thereto and is adapted to carry a record which is engaged by the tone arm *b* of such apparatus. The tone arm of apparatus of this character is pivotally mounted at a point such as *c* some distance away from the axis of rotation of the turn table and the weight of such arm is supported by a needle *b'* in the head of the tone arm. The tone arm in operation preferably extends in operating position in substantially a horizontal plane when the needle *b'* rests upon the record *d* to be reproduced. To utilize the apparatus thus described without change, it is necessary, therefore, that any device placed upon the turn table to support the record be quite thin, so as not to disturb the relative angle of the tone arm. A pin *a'* is arranged centrally of the turn table and is approximately one inch long and thus to permit the use of such pin to center my device and the record *d* carried thereby, it is necessary that my device be substantially less than three-fourths of an inch in overall thickness or height. Less thickness or height is desirable although not necessary.

My improved speed change device comprises two discs *e* and *f* arranged in stacked vertical alinement and the lowermost disc *e* is adapted to be arranged upon and carried by the upper surface of the turn table *a*. Such surface is preferably and usually felt-covered, so as to provide a resilient surface which

has a relatively high coefficient of friction, so as to prevent relative slippage of the record of my device. Such disc *e* is preferably made of metal to secure strength and weight and the under surface *e'* thereof is preferably roughened, such as being turned with a relatively coarse-edged tool to increase the relative coefficient friction between the under surface of the disc *e* and the surface of the turn table *a*. As has been noted heretofore, the turn table *a* is commonly provided with a centering pin *a'*, which is in axial alinement with the center of rotation of the turn table, and it is over such centering pin that the record *d* to be reproduced is normally arranged.

Separating the discs *e* and *f* is a centrally arranged upstanding tubular boss *g*, which is secured to, and thus operates with, the disc *e*. The said boss has a bore corresponding substantially to the diameter of the centering pin *a'* over which it fits. Journaled upon such boss and directly overlying the disc *e* is an intermediate member *h* free to rotate with respect to both of such discs *e* and *f*. Overlying the member *h* and having free working clearance with regard thereto is a gear *i*, which is fixed to the boss *g* and thus rotates with the disc *e*. An upstanding stud *l* is carried by the intermediate member *h* at a point spaced from the center of rotation of said member and said stud carries two stacked gear elements *l'* and *l''*, which are free to rotate upon said stud *l*. The smaller of said gears *l''* meshes with the gear *i* and the larger one *l'* meshes with a gear *k*, which latter is fixed to the under surface of the upper disc *f*. The desired difference in rotation set out in the introduction to the specification is secured by proportioning said gears *i*, *k*, *l'* and *l''* with respect to each other. The member *h* is held against rotation by an extensible member *m*, which is adapted to be moved outwardly until it engages one of the stanchions or fixed members of the guard rail *n*, or some other convenient fixed member.

The disc *e* thus rotates with the turntable *a*, being in frictional engagement with such turntable. The gear *i* also rotates with the disc *e*, being fixed thereto. The member *h* is held against rotation, and the disc *f* and thus the record *d*, rotate in the same direction as the turntable *a*, but at an increased rate. The gears are arranged so that when the turntable *a* rotates at $33\frac{1}{3}$ R. P. M., the disc *f* rotates at a speed of 78 R. P. M. The upper surface of the disc *f* carries a felt covering *o*, which frictionally engages and protects the record *d*.

60 I claim:

1. In combination with the turn table and tone arm of sound reproducing apparatus, a relatively flat detachable speed change device comprising two relatively rotatable and axially alined discs, one resting in axially

alinement upon and engaging the turn table, the other carrying in axial alinement and engaging the sound record to be engaged by the tone arm of such apparatus and means operatively connecting said two discs together and proportioned to produce predetermined differential rotation between the latter. 70

2. In combination with a turn table and tone arm of sound reproducing apparatus, a relatively flat detachable speed change device comprising two relatively rotatable and axially alined discs, one resting in axially alinement upon and engaging the turn table, the other carrying in axial alinement and engaging the sound record to be engaged by the tone arm of such apparatus and a train of gears operatively connecting said two discs together and proportioned to produce predetermined differential rotation between the latter. 80 85

3. In combination with the turn table and tone arm of sound reproducing apparatus, a relatively flat detachable speed change device comprising two relatively rotatable and axially alined discs, one resting in axially alinement upon and engaging the turn table, the other carrying in axial alinement and engaging the sound record to be engaged by the tone arm of such apparatus, a member arranged intermediate said two discs provided with a locking device adapted for engaging a stationary portion of such apparatus thereby to fix said member against rotation and means in part carried by said member operatively connecting said two discs together and proportioned to produce predetermined differential rotation between the latter. 90 95 100

4. In combination with the turn table and tone arm of sound reproducing apparatus, a relatively flat detachable speed change device comprising two relatively rotatable and axially alined discs, one resting in axially alinement upon and engaging the turn table, the other carrying in axial alinement and engaging the sound record to be engaged by the tone arm of such apparatus, a member arranged intermediate said two discs provided with an extensible locking device adapted for engaging a stationary portion of such apparatus thereby to fix said member against rotation and means in part carried by said member operatively connecting said two discs together and proportioned to produce predetermined differential rotation between the latter. 110 115 120 125

5. A device for changing the effective speed of sound reproducing apparatus comprising two relatively rotatable discs mounted on a central axis, and means operatively connecting the two discs together and proportioned to produce predetermined differential rotation between the latter. 125

6. A device for changing the effective speed of sound reproducing apparatus comprising two relatively rotatable discs mount- 130

ed on a central axis, the pivotal connection between said two discs having an axial bore extending continuously thru the latter and means operatively connecting the two discs together and proportioned to produce predetermined differential rotation between the latter.

7. A device for changing the effective speed of sound reproducing apparatus comprising two relatively rotatable discs mounted on a central axis, a member arranged intermediate said discs and means in part carried by said member operatively connecting the two discs together and proportioned to produce predetermined differential rotation between the latter.

8. A device for changing the effective speed of sound reproducing apparatus comprising two relatively rotatable discs mounted on a central axis, a member arranged intermediate said discs, the latter provided with a locking device for fixing said member against rotation and means in part carried by said member operatively connecting the two discs together and proportioned to produce predetermined differential rotation between the latter.

9. A device for changing the effective speed of sound reproducing apparatus comprising two relatively rotatable discs mounted on a central axis, the pivotal connection between said two discs having an axial bore extending continuously thru the latter, a member arranged intermediate said discs, the latter provided with a locking device for fixing said member against rotation and means in part carried by said member operatively connecting the two discs together and proportioned to produce predetermined differential rotation between the latter.

10. A device for changing the effective speed of sound reproducing apparatus comprising two relatively rotatable discs mounted on a central axis, a member arranged intermediate said discs, the latter provided with an extensible locking device for fixing said member against rotation and means in part carried by said member operatively connecting the two discs together and proportioned to produce predetermined differential rotation between the latter.

In testimony whereof he has affixed his signature.

LAWRENCE FRITZ.
